Primary Examiner — Darcey E Gottschalk*Assistant Examiner* — Haley K Schnebele(74) *Attorney, Agent, or Firm* — Cramer Patent & Design, PLLC.; Aaron R. Cramer(57) **CLAIM**

The ornamental design for a bottle cap as shown and described.

DESCRIPTION

FIG. 1 is a perspective top front right view of a bottle cap, showing my new design;

FIG. 2 is a rear elevation view thereof;

FIG. 3 is a front elevation view thereof;

FIG. 4 is a left elevation view thereof;

FIG. 5 is a right elevation view thereof;

FIG. 6 is a bottom plan view thereof; and,

FIG. 7 is a top plan view thereof.

The broken lines depict portions of the bottle cap that form no part of the claim.

1 Claim, 3 Drawing Sheets(56)
